UNITED STATES PATENT OFFICE.

ARTHUR BARRETT, OF BELLEVUE, PENNSYLVANIA.

WRENCH.

1,285,899.

Specification of Letters Patent. Patented Nov. 26, 1918.

Application filed May 14, 1917. Serial No. 168,606.

To all whom it may concern:

Be it known that I, ARTHUR BARRETT, a citizen of the United States, residing at Bellevue, in the county of Allegheny, State 5 of Pennsylvania, have invented certain new and useful Improvements in Wrenches, of which the following is a specification.

My invention relates to tools for handling drill-bits or other tools used in drilling or 10 operating Artesian wells and for like purposes, the tools being also applicable generally to the handling of any heavy parts to be screwed together when in a vertical position, whether in connection with Artesian wells 15 or in other mechanical operations. It is an improvement on Letters Patent No. 561,305, dated June 2nd, 1896, issued to Josiah Barrett and is intended to meet a difficulty in the use of tools for handling heavy parts 20 required to be screwed together, owing to the difficulty in turning the revolving member because of the open gap.

My invention consists, generally stated, in providing a swivel ring with a removable 25 segment which when applied closes the gap, forming a complete circle which allows the revolving parts to turn freely on a continuous sliding surface. The said removable part when applied also serves the purpose 30 of preventing the drilling tool from accidentally falling out through the opening while said tool is being handled.

In the accompanying drawings, Figure 1 is a plan view of the tool, Fig. 2 is the section of same, and Fig. 3 is a view of the 35 swivel ring with the removable segment opened.

In the drawings the frame or lever of the wrench is shown at 1, and this may be 40 supported, if desired, by any suitable crane or derrick by means of a chain or block, with a hook or ring passing through the eye 2. This lever has its forward end forked, being provided with the arms 3, 45 which are provided at their outer ends with the eyes or bearings 4. The swivel-ring is shown at 5, and this is mounted in the forked arms by means of trunnion-bolts 6, passing

through the eyes 4 and into said ring 5. This ring is open on one side and is provided 50 with arms or lugs 10 to which is attached a removable segment 8. Mounted on ring 5 is the rotary wrench portion or plate 7, which likewise is open on one side, as shown, to admit of its engagement with and disengagement from the articles to be handled. 55 This plate 7 is bolted with suitable bolts to the carrier ring 11, which allows the use of separate and interchangeable plates for different size articles to be handled. 60

In the use of prior devices of this character the swivel ring 5 has not been provided with the segment 8 to close the gap. This gap being open would prevent the plate 7 and carrier ring 11 from revolving freely 65 within said swivel ring, and would also permit the articles being handled to accidentally fall out when the opening in plate 7 and the opening in swivel ring 5 coincide. By my invention I provide the swivel ring 5 with 70 a suitable segment 8 which closes the gap while the tool is being used. This segment may be fastened as shown in Fig. 1, by suitable bolts 9 or could be arranged to be fastened with a hinged or pivoted connection 75 at the one end and a bolt at the other end as in Fig. 3, enabling the segment 8 to be swung outward and then be quickly closed after the article to be handled has been placed in position in the wrench portion. 80 Various other methods of attaching segment 8 may be substituted by those skilled in the art.

By my improvement the tool-holder or wrench proper of the device is capable of 85 being turned with ease, even when supporting the heaviest article, and the said articles are prevented from accidentally falling out of the wrench portion through the gap.

What I claim as my invention, and desire 90 to secure by Letters Patent, is—

1. In a wrench, the combination of a forked frame, a ring pivotally mounted on the forks thereof; said ring having a gap at one side thereof, a tool holder journaled 95 in said ring to rotate therein, and a segment

arranged to close the gap in said ring, said segment being detachably secured to said ring.

2. In a wrench, the combination of a
6 forked frame, a ring pivotally mounted on
the forks thereof; said ring having a gap
at one side thereof, a tool holder journaled
in said ring to rotate therein, and a segment
arranged to close the gap in said ring, said

segment having one of its ends pivoted to 10
the ring and its other end suitably secured
thereto.

In testimony whereof I hereunto affix my
signature in the presence of two witnesses.

ARTHUR BARRETT.
